INVENTOR:

EDWARD H. ALLEN:

BY

William J. Jackson

ATTORNEY:

UNITED STATES PATENT OFFICE

EDWARD H. ALLEN, OF PALMYRA, NEW JERSEY

SASH FASTENER

Application filed June 10, 1929. Serial No. 369,781.

This invention relates to window sash hardware and has more especial relation to a combined sash fastener and anti-rattler.

One object of the present invention is to provide a sash lock designed to hold the upper and lower sash of a window in secured position when the sashes are either in open or closed position.

A further object is to provide a sash lock of the character stated in which the parts automatically function to interlock an upper and lower sash in closed position.

A further object is to provide a sash lock of the character stated which after automatic locking of its parts may be manually adjusted to prevent sash rattling.

A further object of the present invention is to provide upon the upper sash of a window a pivotal and perforated member which when not in use may be folded over in horizontal position upon the sash lower rail.

With these and other objects in view, the invention consists of the novel construction hereinafter described and finally claimed.

The nature, characteristic features and scope of the invention will be more fully understood from the following description taken in connection with the accompanying drawings forming part hereof, and in which:

Fig. 1, is a fragmentary view of an upper and lower window sash equipped with a sash lock embodying the invention and illustrating the lower sash slightly raised.

Fig. 2, is a view in section taken upon the line 2-2 of Fig. 1.

Fig. 3, is a fragmentary view in section illustrating the upper and lower sash in closed position and the sash lock adjusted to prevent rattling of the sash.

Fig. 4, is a detail view in elevation of the foldable member shown in Figs. 1, 2, and 3.

Fig. 5, is a detail view in elevation of a slightly modified form of sash lock parts; and

Fig. 6, is a view in section taken upon the line 6-6 of Fig. 5.

For the purpose of illustrating my invention I have shown in the accompanying drawings two forms thereof which are at present preferred by me, since the same have

been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the drawings, and referring more particularly to Figs. 1 to 4, the reference numeral 1 designates the upper sash of a window and the reference numeral 2 the lower sash. Fixed to the lower rail 3 of the upper sash 1, as by screws 4, is a bifurcated support 5 having at its top a V-shaped recess 6. Having pivotal relation as at 7 between the prongs of the support 5 is a foldable arm 8 having spaced apertures 9. When in use this arm is vertically disposed as shown in Figs. 1, 2, 3, and 4, but when not in use may be folded or shifted to horizontal position so as to lie upon the top of the lower rail 3 of the upper sash.

A description will now be given of the parts as carried by the lower shaft which contacts with the parts of the upper shaft. Fixed to the top rail 10 of the lower sash 2, as by screws 11, is a support 12 of U-shaped cross-section. Movable endwise through the uprights of said U-shaped support is a horizontally disposed rod 13 the outer end of which is provided with a finger piece 14, and the inner end of which is screw-threaded and is provided with a spherical knob 15. The rod 13 is slideable through apertures in the uprights of the U-shaped support 12 but its inwardly slideable movement is limited by the shoulder of knob 15. Its outwardly slideable movement is limited by the sleeve 17, together with pin 16. Arranged between pin 16 and the inner wall of the outer upright of the U-shaped member and surrounding the rod 13 and its sleeve 17 is a coiled spring 18 for normally forcing said rod 13 toward the upper sash 1.

A description will now be given of the manner in which the sash lock may be operated. Should it be desired to interlock the upper and lower sash in some intermediate position the sash 1 and the sash 2 are moved

with respect to one another as shown in Figs. 1 and 2, and the screw threaded end of rod 13 screwed into an aperture 9 of the arm 8 which, it will be understood, has been swung to vertical position around its pivot point 5. In this way window sashes may be interlocked at desired heights. In closing the lower window sash the parts are automatically interlocked for the reason that the knob 15 of pin 13 first engages within V-shaped notch 6 and as the lower sash is further lowered the said notch acts as a cam surface to force rod 13 outwardly so that when the sash 2 is fully lowered the knob 15 of rod 13 may 10 automatically snap into aperture 19 of support 5 upon the upper sash. While this connection is sufficient to retain the sash in interlocked position, a more secure and rattling-proof connection may be secured by the 15 manual operation of screwing the inner end of rod 13 firmly into aperture 19 to cause the rails 3 and 10 of the sash to form a tight joint.

It may not be desired to employ the arm 8 in which case I use in connection with the parts shown upon the top of the upper rail of sash 2 the support shown in Figs. 5-6, it being understood that this support is secured to the top of the lower rail of sash 1. This 20 support, which is designated 20, is similar in all respects to support 5 with the exception that it is of solid cross-section instead of being bifurcated. In connection with spring pressed rod 13 and its adjuncts the function 25 of interlocking the sash in closed position may be obtained automatically and rattling of the sash prevented.

What I claim is:

1. A combined automatic sash fastener and anti-rattler comprising a U-shaped bracket fixed to the lower sash of a window, a spring pressed rod, the forward end of which is screw threaded, movable through smooth bores in the uprights of said U-shaped member, a pin fixed to said rod to limit rod forward movement, a sleeve upon said rod to limit rearward rod movement, a bracket carried by the upper sash of a window having upon its front face a vertically disposed V-shaped notch and a horizontally disposed screw threaded opening therebelow, said opening being in alignment with said rod with the taper of the wall of said notch leading directly toward said opening, whereby in the closing of the lower sash the end of said rod engages said notch to force said rod against the action of its spring in order that said rod may engage said opening to interlock the sash automatically, said rod 30 when screwed into said opening serving to provide an anti-rattler.

2. A combined automatic sash fastener and anti-rattler comprising a U-shaped bracket fixed to the lower sash of a window, a spring pressed rod, the forward end of

which is screw threaded, movable through smooth bores in the uprights of said U-shaped member, a pin fixed to said rod to limit rod forward movement, a sleeve upon said rod to limit rearward rod movement, a bracket carried by the upper sash of a window having upon its front face a vertically disposed V-shaped notch and a horizontally disposed screw threaded opening therebelow, said opening being in alignment with said rod with the taper of the wall of said notch leading directly toward said opening, whereby in the closing of the lower sash the end of said rod engages said notch to force said rod against the action of its spring in order that said rod may engage said opening to interlock the sash automatically, said rod when screwed into said opening serving to provide an anti-rattler, and an arm pivoted to the bracket having the notch therein, said arm having spaced screw threaded apertures therein and being arranged to be swung into vertical position so that said rod may be screwed into an aperture of said arm to fasten the upper and lower sashes at predetermined heights.

EDWARD H. ALLEN.
